UNITED STATES PATENT OFFICE.

HENRY A. WEIHMAN, OF PHILADELPHIA, PENNSYLVANIA, ASSIGNOR TO JOHN F. SIMONS AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY.

DESIGN FOR A BACK FOR BRUSHES, &c.

SPECIFICATION forming part of Design No. 29,218, dated August 16, 1898.

Application filed June 15, 1898. Serial No. 683,522. Term of patent 7 years.

To all whom it may concern:

Be it known that I, HENRY A. WEIHMAN, of the city and county of Philadelphia and State of Pennsylvania, have invented a new and 5 original Design for the Backs of Brushes or Similar Articles, of which the following is a specification.

My design is shown in the accompanying drawing, which is a plan view of a hair-brush 10 back and handle having my design applied.

One portion of the design resides in the surface ornamentation of the body portion of the back of the brush, mirror, or similar toilet article. The upper portion A of the ornamentation is a modified Louis XIV pattern, composed of the fluted portions *a a* on opposite sides, bordered by the foliate ornamentations *b b*, meeting at the top and capped by the floral ornamentation C, with the borderings *d d* of beading upon the inner edge of the fluting *a a*, the whole inclosing an unornamented center *e*. The lower portion B is a modified Renaissance ornamentation, composed of a conventional oak-leaf pattern *f f*, 25 extending upward from the base on each side

of the unornamented center *e* and capped at the base by a floral pattern *g*.

Another portion of the design resides in the surface ornamentation of the handle C'. This consists of combined Louis XIV and Renaissance patterns, composed of flutings *h h* on opposite sides of the outer portion of the handle, bordered on the outside by foliate ornamentations *i i*, meeting at the top and capped by a floral ornamentation *j*, the whole inclosing an unornamented central portion *k*, with a conventional foliate or oak-leaf ornamentation *l* extending forward from the stem of the handle to the fluted portions *h h*. 30 35

What I claim as new, and desire to secure 40 by Letters Patent, is as follows:

The design for the back of a brush or similar article substantially as shown and described.

In testimony of which invention I hereunto 45 set my hand.

HENRY A. WEIHMAN.
